WATER-COOLANT SUPPLY MEANS FOR AN OUT-BOARD PROPULSION UNIT

Charles F. Alexander, Jr., Oshkosh, Wis., assignor to Kiekhaefer Corporation, Fond du Lac, Wis., a corporation of Delaware

Filed Sept. 28, 1962, Ser. No. 226,804
5 Claims. (Cl. 115—17)

This invention relates to an outboard propulsion unit for watercraft and more particularly to a water-coolant supply means for such a unit.

Water-coolant supply means are commonly provided in outboard propulsion units to provide the cooling water for circulation through the engine driving the unit and/or portions of the unit. Generally the inlet for the cooling water is provided in the propulsion unit beneath the anti-cavitation plate or in the gear case housing or in the lower portion of the propulsion unit between the anti-cavitation plate and the gear case housing. For utility outboard propulsion unit operation wherein the lower portion of the unit including the anti-cavitation plate is normally submerged, inlets so disposed are capable of providing an adequate supply of coolant.

Propulsion units for racing, however, usually operate under surface pitch conditions wherein the gear case housing may be wholly out of the water with only a portion of the propeller in the water, presenting considerable difficulty in obtaining an adequate supply of coolant. It is generally an object of this invention to provide a coolant supply means for an outboard propulsion unit which is better able to provide an adequate supply of coolant when operating at high speed under surface pitch conditions.

Generally according to this invention, an adequate coolant supply is provided by a water-coolant supply means in the outboard propulsion unit which includes provision for water inlet means spaced beneath the gear case housing in the skeg of the unit. With the water inlet placed in the skeg and in spaced relation beneath the gear case housing, the inlet will normally be submerged even when operating the propulsion unit at high speed under surface pitch conditions.

The drawings furnished herewith illustrate the best mode of carrying out the invention as presently contemplated and described hereinafter:

In the drawings:

FIGURE 1 is a side elevation of an outboard motor which employs the coolant supply means of this invention;

FIG. 2 is an enlarged side elevation partially in section of the lower portion of the outboard motor of FIG. 1 and shows certain details of the coolant supply means of this invention;

FIG. 3 is a sectional view taken generally on line 3—3 of FIG. 2; and

FIG. 4 is a sectional view taken generally on line 4—4 of FIG. 2.

As shown in the drawings, the invention is illustrated as applied to an outboard motor 1 having a drive shaft housing 2 supporting at the upper end thereof an engine, not shown, enclosed within a cowl 3 and at the opposite end thereof a lower housing 4. The motor 1 is removably secured to the transom 5 of a watercraft 6 by means of a bracket assembly 7 providing for tilt movement of the motor unit in a generally vertical plane on a generally horizontal tilt pin 8 and steering movement in a generally horizontal plane on the generally vertical swivel pin 9.

The lower housing 4 includes the vertical strut portion 10 adapted at its upper end for securement to the drive shaft housing 2, a gear case 11 beneath the strut portion, and a skeg 12 beneath the gear case. The drive shaft 13

2

extends downwardly within housing 2 and strut portion 10 and drivingly connects the engine with the generally horizontal propeller shaft 14 rotatably disposed in gear case 11 through meshing bevel gears 15 and 16 in gear chamber 17. The propeller shaft 14 extends from a position intermediate the length of the gear case rearwardly through an opening in the gear case and carries the propeller 18 rearwardly thereof.

The gear case 11 includes a coolant chamber 19 forwardly of gear chamber 17, and a closure member 20 having a diameter which corresponds generally with the bore in the gear case separates the chambers. The coolant chamber 19 is closed forwardly by a generally conically shaped end cap 21 which extends over the opening 22 to the chamber. The closure member 20 includes a forwardly extending stem portion 23 for securing the cap 21 in position over opening 22 with the stem portion being generally in alignment with the propeller shaft 14 in gear chamber 17 and extending forwardly through the annular support sleeve 24 to properly center the stem portion within the coolant chamber.

The closure member 20 engages with shoulder 25 within gear chamber 17 to axially position the member within the gear case bore and is spaced axially from support sleeve 24 by means of an annular spool-like member 26 to be further described hereinafter. The closure member 20 along with the spool-like member 26 and support sleeve 24 are secured within the coolant chamber 21 by means of the snap ring 27 partially recessed in the wall of the gear case bore forwardly of the support sleeve. An annular sealing member 28 is disposed in a peripheral recess 29 formed between the spool-like member 26 and the adjacent stepped edge of closure member 20 to seal the coolant chamber 19 from the gear chamber 17.

The end cap 21 serving as the forward closure for coolant chamber 19 is secured in position by the axially extending pin member 30 which is threaded rearwardly thereof to threaded engage with a correspondingly threaded bore opening 31 in the forward end of stem portion 23 to secure the end cap over the gear case opening 22. Rearwardly the outside diameter of the end cap 21 corresponds generally with the outside diameter of the gear case 11 so as to present a smooth juncture therebetween. The end cap 21 is stepped rearwardly to provide an annular radial shoulder 32 adapted for engagement with the forward end edge of the gear case at opening 22 and an annular flange 33 inwardly and rearwardly of shoulder 32 extends into gear case opening 22 and serves to properly align the cap with respect to the gear case upon closure.

The skeg 12 beneath the gear case 11 is provided with a coolant cavity 34 which receives the coolant for circulation through the inlet opening 35 in the leading or forward edge of the skeg and spaced beneath the gear case.

The coolant cavity 34 in skeg 12 is provided with a generally T-shaped cross section intermediate the fore-and-aft extremes thereof as is most clearly shown in FIG. 3. The lower portion of cavity 34 is relatively narrow transversely so as to maintain the relatively narrow characteristic of the skeg. The upper relatively wide portion of cavity 34 extends beneath the gear case 11 and beneath corresponding portions of coolant chamber 19 and gear chamber 17.

From skeg cavity 34 the cooling water is conducted into the coolant chamber 19 through a plurality of ports 36 provided in the wall of gear case 11 in alignment with the spool-like member 26 and enters the peripheral recess 37 formed between the peripheral flanges 38 and 39 of the spool-like member. Upon entering the peripheral recess 37 of the spool-like member 26, the water is conducted into the annular cavity 40 around the stem por-

tion 23 of closure member 20 and interiorly of the spool-like member through a plurality of circumferentially spaced ports 41 in the annular web portion 42 of the spool-like member connecting flanges 38 and 39.

From the cavity 40 interiorly of the spool-like member 26, the coolant moves into a generally frustoconical cavity 43 formed in the adjacent side of the centering support sleeve 24 and through the axially extending circumferentially spaced passages 44 provided in sleeve 24 spaced intermediate between stem portion 23 and the wall of the gear case bore and into the forward portion of the coolant chamber 19.

After moving through gear case chamber 19, the water for cooling is conducted through the lower housing passage 45 communicating with chamber 19 to areas of the propulsion unit and/or engine where cooling is desired. A pump, not shown, may be disposed in communication with passage 45 above the anti-cavitation plate 46 and be driven from drive shaft 13 to provide for circulation of coolant at the desired pressure.

The lower housing 4 of this invention is particularly adapted for racing propulsion units wherein the gear case 11 may be wholly out of the water with the propeller 18 operating under surface pitch conditions as generally shown in FIG. 2. With the inlet opening 35 provided in the skeg 12 and spaced beneath the gear case 11, a substantially constant and adequate supply of coolant will be available in such racing units. During periods when the propulsion unit is operated at racing speeds with gear case 11 wholly out of the water, the invention also provides for a degree of cooling for gear chamber 17 as the fresh circulating coolant flows around portions of the gear chamber through skeg cavity 34 and coolant chamber 19.

Various modes of carrying out the invention are contemplated as being within the scope of the following claims particularly pointing out and distinctly claiming the subject matter which is regarded as the invention.

I claim:

1. In an outboard propulsion unit for watercraft, said unit having a lower portion including a gear case for

rotatably supporting a generally horizontal shaft carrying a propeller rearwardly of the gear case, a cooling water circulation system in said unit and including a hollow skeg extending downwardly from said gear case and having a heat exchange surface constituting a wall of said gear case and water inlet means in said skeg supplying water to said system through the hollow interior of said skeg and spaced substantially beneath said gear case.

2. The invention as set forth in claim 1 wherein the water inlet means comprise at least one opening forwardly in said skeg.

3. The invention as set forth in claim 1 wherein the water inlet means comprise at least one opening in the leading edge of said skeg.

4. In an outboard propulsion unit for watercraft, said unit having a lower portion including a gear case and a skeg beneath said gear case, said gear case having a chamber rearwardly therein for rotatably supporting a generally horizontal shaft with the shaft projecting from the chamber and carrying a propeller rearwardly of the gear case and for housing the drive gears for said shaft; a cooling water circulation system in said unit and including passage means in said gear case forwardly of the gear chamber, a cavity in said skeg communicating with said passage means, said cavity comprising top and side walls, said top wall constituting at least a portion of the bottom of the gear chamber and providing heat exchange means therebetween, and water inlet means in the skeg opening into said chamber.

5. The invention as set forth in claim 4 wherein the skeg cavity is provided with a generally T-shaped cross-section with the relatively wide portion thereof extending beneath at least a portion of said gear chamber to provide for a measure of cooling for said chamber when the propulsion unit is operated under surface pitch conditions with the gear case out of the water.
